Letter Patent No. 2,317, Dated May 15, 1966

Design for a knife handle

The subject referred to in these letters Patent and making part of the same

Will claim it as:

Bert Knoebel, of Elkhorn, Oshkoshine, of the town of Elkhorn, Meeker County, Indiana, his agent and assignee, Design for a knife-handle, of which the following is the most exact description, reference being had to the drawing, making part of this specification.

I give my knife handle the form and finish of a fish. The cheeks of the handle, above and below, are carved and finished in imitation of head and tail respectively. I also imitate the gills on the head, and the tail fins appear on the otherwise, and the gills through the upper, or head cheek mouth, the eyes. The cover of the handle is shaped so as to represent the sides of the fish and are carved in imitation and to represent the scales.

I claim the above design for a knife-handle as shown and described.

Witness,

Bert Knoebel
